UNITED STATES PATENT OFFICE.

RENÉ VICTOR NINCK, OF NICE, FRANCE.

PRESS OF THE COMPRESSED-AIR TYPE FOR THE CASTING OF PRECIOUS METALS.

Application filed February 29, 1924. Serial No. 695,947.

To all whom it may concern:

Be it known that I, RENÉ VICTOR NINCK, citizen of the French Republic, residing at Nice, in the Department of Alpes-Maritimes,

5 France, have invented new and useful Improvements in Presses of the Compressed-Air Type for the Casting of Precious Metals, of which the following is a specification.

10 My invention relates to presses which are employed in the art of moulding on the lost wax principle wherein the melted metal is cast in the mould under pressure, for the obtainment of dental pieces, goldsmiths' work and the like objects.

Various means have been employed in the lost wax process whereby the metal is forced into all parts of the mould. The process termed "slag process" or centrifugal process which is still in use at the present time by dentists and goldsmiths requires considerable skill and is attended with an unduly rapid cooling, besides producing irregular results. Presses of known types are employed which operate by compressed air from an outside source (pumps, reservoirs, conduits and the like), but such apparatus require an installation of some size; the expense of the plant is considerable and the operation becomes more difficult because various cocks or valves are to be manipulated and a pressure-gauge must be observed; the difficulties are further increased from the necessity of operating in a very rapid manner in order to obviate the drawbacks due to cooling. Other apparatus make use of presses of the steam pressure type, applying moistened asbestos upon the preliminarily heated mould but such presses are inconvenient because the pressure is abruptly produced, and it is impossible or at least very difficult to limit the pressure, resulting in the distortion of the mould, the expansion of the melted metal, the formation of burrs and blisters, while on the other hand the cooling is too rapid, so that the metal may be solidified before the moulding operation is completed.

The invention relates to a press of the known self-contained type which comprises a lever-controlled air pump which is so disposed that when a part of the pump serving as a closing plate (e. g. the bottom of the pump cylinder) is applied upon the envelope

simply necessary to operate the said lever so as to compress the air in the pump and to deliver it directly into the mould through a suitable aperture in the closing plate.

My invention has for its object to provide 60 a press of said type which is readily manipulated and can be operated by any person by reason of its entirely automatic action, and which is of a very simple construction and can be manufactured at a comparatively 65 small expense.

My improved press is chiefly characterized in that the relative displacement of the closing plate of the pump and the mould as well as the operation of the pump are obtained by means of a single operating lever, in such manner that the continuation of the movement of closing the mould will act to set up the pressure within the said mould, or otherwise stated, the closing plate of the mould is combined with a device controlling the other part of the pump, so that the displacement of the control element which produces the relative movement between the mould and its closing plate will in the first 80 place press the said plate upon the top of the mould in order to close the same, and will then compress the air within the body of the pump in order to deliver the air into the mould. The pump cylinder is for instance movable upon its slides so that the bottom of the same shall be applied against the envelope of the mould, with interposition of a packing member, and the displacement of the said cylinder will no longer be 85 effected by positive control, but through the intermediary of a spring interposed between the same and a piston-controlling lever, whereby the descent of the lever will bring the said cylinder upon the mould at a pressure which is limited by the spring, and will then displace the piston in its cylinder, compressing the spring and at the same time delivering the compressed air into the 90 mould.

The invention further relates to various detail arrangements and chiefly for regulating the air pressure, and also for the purpose of facilitating (and if necessary rendering 95 automatic) the extinction of the blowpipe jet employed for the heating of the mould.

The appended drawings show by way of example an embodiment of the invention. Fig. 1 is a general sectional view of the apparatus upon the longitudinal axis; Fig. 110

2 is a transverse section on the line II—II, Fig. 1, and Fig. 3 is a plan view.

The apparatus comprises a ribbed base plate 1, as above explained, having formed therein a cylindrical cavity 2 having the centre line O—O and containing the filling rings 3, 3 of different diameters, whereby various envelopes of moulds having different diameters (such as M shown in dotted line) can be disposed in the same upon a packing disc 4, in the known manner. To the said base plate are secured two guide rods 5 having a diametrically opposite position with respect to the centre line O—O and serving as guides for the pump cylinder G which is slidable thereon by means of the lugs 6. The said cylinder is held in position upon said guide rods by the set screws 7. The cylinder is closed by a cover 8 which is pierced with an aperture for the inlet of air which is withdrawn from the exterior; said cylinder co-operates with a piston made of pressed leather 9 which is mounted at the end of a rod 10 pivoted at 11 to the operating lever 12 having the handle 12', said lever being pivoted by means of the link 13 to the fixed point 14.

The pivoting arrangement 14 comprises a fork 15' disposed at the end of a rod 15 which is slidable in a socket 16 bolted to the base plate 1, and which may be secured in position in said socket by the set screw 17, whereby the height of the pivoting point 14 above the base plate can be varied, according to the height of the envelope of the mould. A spring 18 abuts respectively against a shoulder on the piston rod 10 and the cylinder cover 8, so that when the said cylinder is held in the raised position by means of the screw 7, the lever 12 will be maintained in the raised position, Fig. 1.

The bottom of the cylinder p constitutes a closing plate for the envelope of the mould, and to this effect it is ribbed at the bottom in order to co-operate with a plastic disc which forms a fluidtight joint with the edge r of the envelope M of the mould. The bottom p is pierced with a central orifice 19.

It is observed that by lowering the handle 12' (after disengaging the set-screw 7) the end p of the cylinder is brought upon the edge r of said envelope, thus forming a tight joint. But when this motion is continued, the piston 9 will move within the cylinder G and consequently while the plate p closes the mould with a force determined by the compression spring 18, the compressed air is forced by the piston through the aperture 19 into the mould whereby the latter shall be entirely filled with the metal.

The cover 8 of the cylinder is provided with a stop-plate 20 mounted thereupon by means of the screw 21 and pivoting upon the said screw; a spring 22, Fig. 3, consisting for example of a spring strip secured to

the screw 21 and to a screw 23 mounted upon said cover, acts by its outer end 24 upon the edge of the stop-plate 20 so as to urge the plate against the piston rod 10 whereby it is made to co-operate with the saw-toothed portion 25 formed upon the said rod. The said plate can be disengaged from the piston by means of the small button 26 mounted upon the plate. The initial position of said piston in its cylinder can thus be varied so as to regulate the length of the remainder of the stroke after the end of the cylinder p comes into contact with the mould envelope M, and hence to regulate the air pressure at the end of the stroke. The said blade or stop-piece also serves to lock the piston with reference to the cylinder at the end of the compression stroke, so that when the said lever has been lowered to the maximum, it suffices to screw in the screw 7 in order that the said cylinder shall be held against the mould and that the pressure shall be maintained therein, without being obliged to maintain the lever by hand.

It will be observed that the spring 18 serves to ensure the necessary pressure for the fluidtight action of the joint during the movement of the piston in the cylinder, in spite of the action of the compressed air exercised below the plate p within the mould envelope M.

The gas burner 27 provided with the connecting nipples 28 is pivoted to a rod 29 slidable in a socket 30 and held in position by the set screw 31, the socket 30 is secured to the base plate 1 by a nut screwed upon the lower screwthreaded end of the socket which traverses a radial slot 32 in the said plate. In this manner, the spacing of the said burner as well as its height above the mould envelope can be regulated at will with reference to the height of the mould by displacement of the socket 30 in its slot and of the rod 29 in its socket 30.

According to the invention, the pivot of the burner 27 upon the rod 29 forms a valve whose drum is constituted by the tube of the burner and the outer part 34 by a supporting spindle 29, so that it will suffice to lower the burner by hand upon its pivot in order to cut off the gas supply and thus to extinguish the burner, while at the same time one allows a free passage for the said cylinder. The device can even be so combined that the contact between the lower edge of the said cylinder against the burner shall automatically effect the rotation and consequent extinction of the latter.

It will be observed that the burner is adjustable in the socket 30 by means of the set screw 31 and it will be seen that the said burner can be adjusted with respect to various heights of moulds. In order to insure the automatic movement of the gas

burner away from the mould and the consequent extinguishment of its flame, it is only necessary to raise the burner a sufficient height above the top of a mould so that as the piston cylinder moves downward it will engage the burner, to rotate it downwardly on its axis to clear the top of the mould and extinguish the flame. This is obviously an important feature since the construction permits of the automatic removing of the burner and at the same time cooperates with the valve construction provided to extinguish the flame.

The operation is as follows:

The envelope M and the mould are placed in position after the usual heating operation and after the removal of the rings 3 having a smaller diameter; the height of the pivot 14 and the height of the burner are respectively adjusted by the screws 17 and 31 according to the diameter and height of the mould, and the initial position of the piston in its cylinder is determined according to the desired pressure by a partial lowering of the lever 12. After these operations have been performed, the metal which is to be cast in the mould is heated by the burner in the known manner, and when the stated temperature is attained the screw 7 is unscrewed, the handle 12' is lowered to the maximum by a single movement and the screw 7 is screwed up. The cylinder closes the mould in an automatic manner, moving aside and extinguishing the burner, and compressed air has been admitted to the interior of the mould. In this manner the operation is quite instantaneous; no cooling effect is to be apprehended and the pressure is limited exactly to the desired degree; the control is very simple and entirely automatic, and the operation can now be performed by an apprentice or a person who is entirely unskilled in the art. On the other hand, the apparatus is portable, self-contained and independent of all outside sources of compressed air; its construction is simple and substantial, resulting in a comparatively inexpensive construction.

Obviously, the form of construction hereinbefore described is given solely by way of example, and it is susceptible of all desired modifications without departing from the principle of the invention; for example, the fitting of the said cylinder upon the mould in order to close the same may be controlled by a lever which is independent of the lever controlling the piston in order to obtain the pressure, but the operation will be less rapid and convenient. Instead of using a fixed mould and a movable cylinder, the inverse disposition may be employed; instead of constituting the closing plate p by the bottom of the cylinder, it may be constituted by the piston itself, and

in this case the control lever is connected with the cylinder; the pressure obtained at the end of the stroke need not be regulated by the variation of the initial position of the piston in the cylinder, but it may be regulated by varying the final position of the piston in the cylinder, using for the purpose the ratchet connection between the cylinder and the piston rod. The bottom part p has been shown as integral with the said cylinder, but in actual construction it preferably consists of an interchangeable base, so that its diameter may be varied according to the diameter of the envelope M.

Claims—

1. A press for casting metals under pressure in moulds of the lost wax type, comprising a pump cylinder movable upon guides which are vertical in principle, the bottom of said cylinder being apertured near the centre and constituting the closing plate of the mould casing, a piston provided with a rod and movable in the said cylinder, means for controlling the said piston through the medium of its rod, and a spring interposed between the said controlling means and the pump cylinder in order to apply the said plate upon the mould with elastic force and to subsequently allow the piston to move in the said cylinder under the positive action of said controlling means, with compression of the said spring, ratchet means provided between the said pump cylinder and the piston rod whereby the cylinder may be secured to the piston when in any given position and at any suitable moment of the operation.

2. A press for casting metals under pressure in moulds of the lost wax type, comprising a pump cylinder movable upon guides which are vertical in principle, the bottom of said cylinder being apertured near the centre and constituting the closing plate of the mould casing, a piston provided with a rod and movable in the said cylinder, means for controlling the said piston through the medium of its rod, and a spring interposed between the said controlling means and the pump cylinder in order to apply the said plate upon the mould with elastic force and to subsequently allow the piston to move in the said cylinder under the positive action of the said controlling means, with compression of the said spring, a set screw being disposed upon the said cylinder whereby the latter may be secured at any suitable point upon its guides.

3. A press for casting metals under pressure in moulds of the lost wax type, comprising a pump cylinder movable upon guides which are vertical in principle, the bottom of said cylinder being apertured near the centre and constituting the closing plate of the mould casing, a piston provided with a rod and movable in the said cylin-

der, means for controlling the said piston through the medium of its rod, and a spring interposed between the said controlling means and the pump cylinder in order to apply the said plate upon the mould with elastic force and to subsequently allow the piston to move in the said cylinder under the positive action of the said controlling means, with compression of the said spring, ratchet means being disposed between the said pump cylinder and the piston rod whereby the cylinder may be secured to the piston when in any given position and at any suitable moment of the operation, a set screw being disposed upon the said cylinder whereby the latter may be secured at any suitable point upon its guides.

4. In an apparatus of the class described, a flask, a pump for supplying air to said flask, said pump comprising a cylinder and piston, means formed on the stem of said piston for cooperating with means formed on said cylinder for adjusting the relationship of the cylinder and piston whereby the amount of air supplied to said flask may be varied.

5. In an apparatus of the class described, a flask, a pump for supplying air to said flask comprising a cylinder and a piston, ratchet teeth formed on said piston, a ratchet member formed on said cylinder for cooperating with said teeth whereby the amount of air delivered to said flask may be varied.

6. In an apparatus of the class described, a flask, a pump for supplying air thereto comprising a cylinder and piston, means formed on said cylinder and piston for regulating the amount of air supplied to said flask, and a heating member for said flask adapted to be moved to inoperative position when said pump is operated.

7. In an apparatus of the class described, a flask, a pump for supplying air thereto comprising a cylinder and piston, means formed on said cylinder and piston for regulating the amount of air supplied to said flask, an adjustably mounted blow torch

adapted to be engaged by said pump and moved to inoperative position.

50

8. In an apparatus of the class described, a base, a flask mounted thereon, an operating member pivotally and adjustably mounted on said base, a piston operable by said operating member, and a cylinder resiliently mounted on said piston whereby movement of the operating member will serve to discharge air from said cylinder into said flask.

55

9. In an apparatus of the class described, a base, a flask mounted thereon, an operating member pivotally and adjustably supported by said base, a piston connected to said operating member, and a cylinder mounted on said piston and adjustable with relation thereto whereby when said member is operated the cylinder closes the open end of said flask and the amount of air supplied may be regulated.

60

65

10. In an apparatus of the class described, a base, a pump mounted for movement on said base and having a cylinder and piston, said pump being adapted to form a closure for the mould and such closure portion having an opening formed therein, means for adjusting the position of the pump with respect to said base, a spring acting between the cylinder and the piston, the piston having a serrated portion and the cylinder a ratchet whereby the piston and cylinder may be adjusted with relation to each other, to vary the pressure in the mould, a single operating lever for moving said pump to close the mould and for actuating the piston to force air into said mould, and a burner adjustably and pivotally mounted on said base and having a fuel valve actuated by movement about its pivot, said burner being adapted to lie in the path of movement of the pump whereby as the pump descends to close the mould, the burner will be automatically moved away from the mould and about its pivot to extinguish the flame.
